UNITED STATES PATENT OFFICE

MAGGY BESANÇON DE WAGNER, OF PARIS, FRANCE, ASSIGNOR TO LENTHERIC, INCORPORATED, OF NEW YORK, N. Y., A CORPORATION OF NEW YORK

DESIGN FOR A BOTTLE

Application filed November 5, 1929. Serial No. 33,346. Term of patent 14 years.

To all whom it may concern:

Be it known that I, MAGGY BESANÇON DE WAGNER, a citizen of the Republic of France, residing in the city of Paris, France, have invented a new, original, and ornamental Design for a Bottle, of which the following is a specification, reference being had to the accompanying drawing forming a part thereof.

In the drawing,
Fig. 1 is a perspective view of my bottle,
Fig. 2 is a side view and
Fig. 3 is a top view thereof.

I claim:

The ornamental design for a bottle substantially as shown.

MAGGY BESANÇON DE WAGNER.
